US00D783101S

(12) United States Design Patent (10) Patent No.: US D783,101 S
Schweigert (45) Date of Patent: * Apr. 4, 2017

(54) GOLF CLUB HEAD

(71) Applicant: PARSONS XTREME GOLF, LLC,
Scottsdale, AZ (US)

(72) Inventor: Bradley D. Schweigert, Anthem, AZ
(US)

(73) Assignee: PARSONS XTREME GOLF, LLC,
Scottsdale, AZ (US)

() Term: 15 Years

(21) Appl. No.: 29/550,730

(22) Filed: Jan. 6, 2016

Related U.S. Application Data

(60) Division of application No. 29/542,980, filed on Oct. 20, 2015, now Pat. No. Des. 750,186, which is a continuation-in-part of application No. 29/541,175, filed on Sep. 30, 2015, now abandoned, which is a continuation-in-part of application No. 29/538,456, filed on Sep. 3, 2015, now abandoned.

Primary Examiner — Mitchell Siegel

(57) CLAIM

The ornamental design for a golf club head, as shown and described.

DESCRIPTION

FIG. 1 is a top perspective view of a golf club head;
FIG. 2 is a bottom perspective view of the golf club head of FIG. 1;
FIG. 3 is a front elevational view of the golf club head of FIG. 1;
FIG. 4 is a rear elevational view of the golf club head of FIG. 1;
FIG. 5 is a top view of the golf club head of FIG. 1;
FIG. 6 is a bottom view of the golf club head of FIG. 1;
FIG. 7 is a right side view of the golf club head of FIG. 1;
and,
FIG. 8 is a left side view of the golf club head of FIG. 1.
The broken lines are included for the purpose of illustration only. None of the broken lines forms part of the claimed design.

1 Claim, 6 Drawing Sheets
